DESIGN FOR A CAN

Isaac W. England, Passaic, N. J., assignor to Continental Can Company, Inc., New York,
N. Y., a corporation of New York

Application November 14, 1935, Serial No. 59,571

Term of patent 14 years

To all whom it may concern:

Be it known that I, Isaac W. England, a citizen of the United States, residing in the city and county of Passaic and State of New Jersey, have invented a new, original, and ornamental Design for Cans, of which the following is a specification, reference being had to the accompanying drawing, forming part thereof.

In the drawing:—

The essential feature of my design is shown in the drawing in full lines, and the can to which it is applied is shown in broken lines.

I claim:—

The ornamental design for a can, as shown and described.

ISAAC W. ENGLAND.
